United States Patent Office

Des. 187,125
Patented Jan. 26, 1960

187,125

TABLECLOTH

Richard A. Fees, Ardsley, Pa., assignor to Quaker Lace
Company, Philadelphia, Pa.

Application August 13, 1959, Serial No. 57,165

Term of patent 14 years

(Cl. D92—26)

The figure is a plan view of a tablecloth showing my new design. The tablecloth is shown over a dark background to bring out the details of the design.

I claim:

The ornament design for a tablecloth, substantially as shown and described.
